UNITED STATES PATENT OFFICE

2,375,584

ELEVATOR

Mason Lloyd Ramey, San Pedro, Calif.

Application June 12, 1944, Serial No. 539,808

7 Claims. (Cl. 294—90)

This invention relates to elevators used for raising and lowering pipe in oil wells and the like. These elevators are designed to engage about a pipe below the collars or other projection on the pipe. The invention more particularly relates to the class of elevators generally known as side-door elevators, which consist of a body having a bore with a forwardly opening throat adapted to receive the pipe and a laterally swinging gate for closing the throat of the elevator, the door being hinged to the body at one side of the throat and arranged to engage latching mechanism on the opposite side of the throat.

Elevators for handling drill pipe in oil wells, casing or tubing must withstand heavy loads, must be easy and safe to operate so that the pipe or casing held by the elevator cannot become accidentally dislodged from the elevator and dropped.

It is one of the principal objects of this invention to provide an elevator of the class described of simple form and construction in which means are provided for retaining the pipe or casing in the elevator not only when the door is in closed position but when the door is in open position so that the pipe or casing cannot become dislodged from the elevator until the retaining means is manually operated to free the pipe or casing.

Another object of the invention is to provide an elevator of the class described of simple form and construction having a high degree of safety factor in which the door and latching arrangement may be easily manually operated without the usual danger of injury to the workmen.

Other objects and advantages will appear hereinafter from the following description and drawings.

Referring to the drawings, which are for illustrative purposes only:

Fig. 1 is a front elevational view showing an elevator embodying a form of my invention, the elevator being shown supporting a pipe;

Fig. 2 is a sectional plan view on line 2—2, Fig. 1;

Fig. 3 is an enlarged sectional plan view on line 3—3, Fig. 1, showing the gate in closed position;

Fig. 4 is a fragmentary sectional view of a portion of the gate and latching mechanism shown in Fig. 3;

Fig. 5 is a sectional plan view similar to Fig. 3, showing the gate in open position;

Fig. 6 is a front elevational view of the elevator shown in Fig. 5 with the gate in open position; and

Fig. 7 is a view similar to Fig. 5, showing the latching mechanism in a position to free the

throat opening for permitting the pipe either to be engaged by or disengaged from the elevator.

Referring more particularly to the drawings, the elevator consists of a body indicated at 10 having a vertical semicircular bore or socket indicated at 11 for receiving the pipe. This bore or socket is provided with an open throat indicated at 12. The elevator is provided with two laterally extending wings illustrated at 13 having opening 14 to receive links 9 which extend upwardly to the hoisting apparatus. The openings 14 are closed by blocks 15 dovetailed into the wings as indicated at 16, the blocks being held in place by bolts 17 which extend through the wings into the blocks. It must be understood that these blocks remain in place during the use of the elevator after the links have been inserted in the holes 14.

Hinged at one side of the throat 12 and forwardly of the center line of the elevator is a swinging door or gate 20 mounted to freely swing on a pin or rod or shaft 21, the door being provided with a handle 22 which may be grasped for manual operation of the door. The door is recessed as indicated at 23 and is provided with an opening or open slot indicated at 24 formed in a rib hereinafter referred to, such opening being arranged to permit swinging of the door freely of engagement of a lug on the locking member hereinafter more specifically described. The recess 23 is provided with a fin or rib 25 which is adapted to be engaged by a locking member, or latch as hereinafter more specifically described.

On the front of the elevator and opposite to the door 20 is a locking member or latch generally indicated at 30. This locking member is mounted on a pin or shaft indicated at 31 forwardly of the center line of the elevator which extends through bosses 32 formed on the front of the elevator. The hinges of the door 20 and the hinges of the locking member 30 both being forward of the center of the elevator, the elevator is not weakened as is the case where the pivoted point of the door and locking member are near or on the center line of the elevator.

The locking member or latch is provided with a lug or projection indicated at 33 which extends beyond the inner edge of the locking member indicated at 34. The latch is yieldingly held with the lug 33 extending partially across the open throat of the elevator as shown in Fig. 5. This is accomplished in the following manner. The lower boss 32 is recessed as indicated at 35 to receive a coiled spring indicated at 36, one end of the spring being secured to the pin or shaft 31 as indicated at 37 and the lower end of the spring being secured

to a pin indicated at 38 mounted in the lower boss. The action of this spring is to yieldingly hold the latch in the position shown in Fig. 3, such movement being limited by the engagement of a hump 39 on the locking member or latch engaging the side wall of the elevator indicated at 40 between the upper and lower bosses. The latch 30 is provided with an outwardly extending handle indicated at 41 by means of which the latch may be swung against the action of the spring free of the throat opening into the position shown in Fig. 7. The elevator is also provided with handles indicated at 42 by means of which the elevator may be grasped and the elevator manually moved into engagement with the pipe as it approaches the derrick floor and when being used to pull pipe from the well.

In actual use, generally the door of the elevator is standing open at the time when the elevator is caused to engage the pipe, having been left open when the previous disengagement was made. Assuming that it is desired to engage the pipe in the elevator, the operator manually positions the elevator about the pipe.

In case the door of the elevator is closed and assuming that it is desired to engage the pipe in the elevator, the latch is swung into the position shown in Fig. 7 and the door is manually opened, the operator then manually positioning the elevator about the pipe. This leaves the throat opening to the bore entirely free of the door so that the pipe may be placed in the bore in the position shown in Fig. 7. When the pipe has entirely entered the bore it is then in the position commonly known as the lifting position. If the pipe does not fully enter the bore of the elevator the tension of the spring on the latch tends to automatically eject the pipe so that it cannot be lifted and possibly dropped due to the fact that it has not been properly placed in the bore. As the pipe enters the bore it moves the latch against the action of the spring 36 and as the pipe enters the bore it presses back the latch into open position by engagement with the lug 33 on the latch, and when the pipe is finally in the bore the latch, due to the action of the spring, moves into the position shown in Fig. 5. When in this position, although the door is open, the pipe indicated at 45 cannot become disengaged from the elevator due to the fact that the lug 33 on the latch stands part way across the throat as shown in Fig. 5. When the pipe has been so engaged the door 20 may be swung into closed position as shown in Fig. 3 and during this movement the fins 25 on the door engage the front portion of the latch and move the latch until the fins have become engaged by the front edge of the latch as shown in Fig. 4 so that the door cannot be opened until by manual movement of the handle 41 the latch is swung out of disengagement with the door.

It is particularly to be noted that unless the pipe moves past the latch and into the bore of the elevator into what is termed the lifting position, that the elevator will not engage the pipe. This is different from the ordinary conventional elevator as with the conventional elevator there is no provision made for insuring that the pipe is in proper position before the lifting operation takes place, with the result that in many instances accidents result because of only a partial engagement of the elevator under the collar of the pipe. In other words, to hold the pipe securely, the conventional form of elevator requires a substantial door which it is necessary

to place in locked position, otherwise the pipe may become disengaged. In my elevator when the pipe has entered the bore and the safety latch has moved to its normal position in front of the bore, the elevator may be used without closing the door, the door merely being an additional means of security.

In actual use, the elevator when it is lowered to the floor to be attached to the pipe when pulling the pipe from the well, usually the gate is standing open. Also, it is at this particular time that the operator grasps the two handles 42 for the purpose of manually positioning the elevator about the pipe as it is held in position by the slips.

When running pipe in the hole, the procedure is partially reversed; that is, the elevator is elevated to the top end of the stands of pipe adjacent to the finger-board of the derrick with the gate standing open. At this point, to manually position the elevator about the top end of the pipe, the operator usually does so by grasping two handles (not shown) which are on the elevator links 15 about two feet above the eyes or openings 14, or he may grasp one link 15 and the handle of the door. At the floor position the operator stands at the back side of the elevator when manually positioning the same on the pipe. At the finger-board position, the operator stands in front of the elevator when he manually positions the same on the pipe.

While I have shown the bore of the elevator with substantially straight walls it is to be understood that the bore may be shaped, as is conventionally done, to accommodate upset tubing or other pipe.

Although one form of the invention has been particularly shown and described, it is contemplated that various changes and modifications can be made without departing from the scope of the invention and it is intended to cover such changes and modifications as come within the scope of the claims.

I claim as my invention:

1. An elevator comprising: a body member having a bore with an open throat; a gate hingedly mounted on the body member arranged to swing in a horizontal plane across the throat into closed position to retain a pipe therein; a locking member pivotally mounted on said body so as to engage said gate when in closed position, and a lug on said locking member extending partially across the throat in the body member when the gate is in open position.

2. An elevator comprising: a body member

having a bore with an open throat; a gate hingedly mounted on the body member arranged to swing in a horizontal plane across the throat into closed position to retain a pipe therein; a locking member pivotally mounted on said body so as to engage said gate when in closed position, a lug on said locking member extending partially across the throat in the body member when the gate is in open position; and yieldable means engaging said locking member so as to yieldingly hold the locking member with said lug extending partially across the open portion of said throat.

3. An elevator comprising: a body member having a bore with an open throat at one side thereof; a gate member hingedly mounted on the

body at one side of said throat arranged to swing in a horizontal plane across the throat to close the throat and thereby retain a pipe therein; a locking member pivotally mounted on said body at the opposite side of the opening to engage said gate when in closed position; an extension

on said locking member extending partially across the throat in the body member when the gate is in open position and spring means mounted on the body member and engageable with the locking member to yieldingly hold the locking member with the extension on the locking member extending partially across the open portion of said throat so as to prevent the pipe from becoming disengaged from the elevator when the gate is in open position.

4. An elevator comprising: a body member having a vertical bore with an open throat at the front thereof; a gate hingedly mounted on the body member at one side of the said throat and forwardly of the center line of the body member, said gate being arranged to swing in a horizontal plane across the throat into closed position to engage a pipe in said bore; a locking member pivotally mounted on said body at the other side of said throat and forwardly of the center line of said body member so as to engage the gate when the gate is in closed position; a projection on said locking member extending partially across the throat in the body member when the gate is in open position and yieldable means engaging said locking member so as to yieldingly hold the locking member with said projection extending partially across the open portion of said throat.

5. An elevator comprising: a body member having a bore with an open throat; a gate hingedly mounted on the body member arranged to swing in a horizontal plane across the throat into closed position to retain a pipe therein; a locking member pivotally mounted on said body so as to engage said gate when in closed position, a lug on said locking member extending partially across the throat in the body member when the gate is in open position; and yieldable means engaging said locking member so as to yieldingly hold the locking member with said lug extending partially across the open portion of said throat; said gate having an opening therein to freely receive the lug on said locking member as the gate moves into closed position.

6. An elevator comprising: a body member

having a bore with an open throat; a gate hingedly mounted on the body member at one side of said throat arranged to swing in a horizontal plane across the throat into closed position to retain a pipe therein; a rib formed at the outer edge of said gate having an open slot therein; a locking member pivotally mounted on said body at the opposite side of said throat, the inner edge of said body member being adapted to engage the rib on the gate when the gate is in closed position; a lug on said locking member extending partially across the throat in the body member when the gate is in open position, said lug being freely received in the slot in said rib when the gate is in closed position; yieldable means engaging said locking member so as to yieldably hold the locking member with said lug extending partially across the open portion of said throat; and means on the locking member engageable with the body member to limit the movement of said lug across said throat.

7. An elevator comprising: a body member having a vertical bore with an open throat at the front thereof; a gate hingedly mounted on the body member at one side of said throat arranged to swing in a horizontal plane across the throat into closed position to retain a pipe in said bore; a locking member pivotally mounted on said body on the opposite side of said throat engageable with said gate when the gate is in closed position to hold the gate in such position; a projection on said locking member extending partially across the throat in the body member when the gate is in open position and yieldable means engaging said locking member so as to yieldingly hold the locking member with said projection thereon extending partially across the open portion of said throat; said gate engaging said locking member during its movement into closed position to move said locking member out of the path of the gate; and said gate having an opening therein to freely receive the lug on the locking member as the gate moves into closed position.
